REAR VISION MIRROR

Frank N. Mariani, New York, N. Y.

Application June 1, 1956, Serial No. 41,739

Term of patent 14 years

(Cl. D14—6)

FIG. 1

FIG. 2

FIG. 3

FIG. 4

Fig. 1 is a side elevational view of the rear vision mirror, illustrating my new design.

Fig. 2 is a front view of Fig. 1.

Fig. 3 is a rear view of Fig. 1.

Fig. 4 is a plan view of Fig. 1.

The dominant features of my design reside in the portions shown in full lines.

I claim:

The ornamental design for a rear vision mirror, substantially as described and shown.
